UNITED STATES PATENT OFFICE.

JAMES TOMNEY, OF NEW YORK, N. Y.

ELECTRIC BURGLAR-ALARM.

SPECIFICATION forming part of Letters Patent No. 289,471, dated December 4, 1883.
Application filed February 5, 1883. (No model.)

To all whom it may concern:

Be it known that I, JAMES TOMNEY, of New York, in the county and State of New York, have invented a certain new and useful Improvement in Electric Burglar-Alarms, of which the following is a specification.

My improvement relates to electric burglar-alarms of the kind whereby a number of guarded structures are connected with an office where watch is kept.

The improvement consists in the combination of a galvanometer or other device located in the office and capable of giving an alarm on a change of resistance in the circuit, a number of different resistance devices located at a guarded structure, and a mechanism located at a guarded structure whereby these resistance devices may be successively introduced for a desired period into the electric circuit, so that even if a burglar should obtain knowledge as to what resistance was in the electric circuit at the time of closing the guarded structure, such knowledge would be rendered of no avail to him because of the periodical changing of the resistance.

The mechanism employed may consist of a train of wheels impelled by a spring or weight and controlled at the office by means of an electro-magnet located at the guarded structure; or it may consist of a train of wheels located at the guarded structure and adapted to run constantly or for any desired periods.

In the accompanying drawings, Figure 1 is a diagram illustrating an electric burglar-alarm embodying my improvement, and Fig. 2 is a diagram illustrating a burglar-alarm having the improvement embodied in it in a modified form.

Similar letters of reference designate corresponding parts in both figures.

A designates the main battery, located at the office where watch is kept. One pole is connected by a wire, B, to an earth-plate, C, and the other pole is connected by a wire, B', with one of the contact-pieces, a, of a metallic switch, D. From the switch D a wire, B², extends to one end of the coils of a galvanometer, E. From the other end of the coils of this galvanometer a wire, B³, extends to the guarded structure.

A' designates a battery located in the office

and of greater electro-motive force than the battery A. One pole is connected by a wire, B⁴, with an earth-plate, C'. The other pole of this battery is connected by a wire, B⁵, with the contact-piece a' of the switch D. By manipulating this switch either the battery A or A' may be connected with the electric burglar-alarm. To the pivot of the needle of the galvanometer is connected one end of a wire, B⁶, forming a local circuit, the other end of said wire being connected with two contact-pieces, b, with which the needle makes contact when vibrated sufficiently, thereby closing the circuit. This local circuit is provided with a battery, A², and an electro-magnetic bell, F, which is caused to ring upon the closing of the circuit. The contact-pieces b b are shown as consisting of screws inserted through posts wherein they are adjustable.

The wire B³ is connected at the guarded structure to one end of the coils of an electro-magnet, G, which controls the operation of a mechanism, H, whereby a number of resistance devices, I I² I³ I⁴ I⁵ I⁶, are successively introduced into the electric circuit at the guarded structure. This mechanism consists, essentially, of a train of gear-wheels, c c', which are rotated by a weight or a spring under control of the electro-magnets G. I combine with the train of wheels an escapement or a fly, e, to prevent them from rotating too rapidly. On one side of the wheel c' is a pin, f. A lever, g, is pivoted to the frame of the train of wheels, and is affixed at one end to the armature of the electro-magnets G. The other end of the lever extends close to the wheel c', and when the armature of the electro-magnets is not attracted thereby this end of the lever is actuated by a spring, so as to obtrude itself in the path of the pin f and block the train of wheels. When the armature of the electro-magnets is attracted by them, the lever is moved out of the path of the pin f and the train of wheels is free to rotate under the influence of their spring. The battery A is not capable of energizing the electro-magnets G to an extent sufficient to cause them to attract their armature; therefore, when the watchman at the office desires to cause the said electro-magnets to attract the armature he switches on the battery A'. This battery is only left on momen-

tarily; hence the electro-magnets attract their armature and then immediately release it, thereby freeing the train of wheels from the lever and allowing the lever to obtrude itself again in the path of the pin f . The train of wheels is therefore allowed to run only long enough for the wheel c' to make a single revolution. If the wheel c' were provided with two or more pins, f , it could be blocked and stopped after making a part of a revolution.

The resistances $I' I^2 I^3 I^4 I^5 I^6$ in this example of my invention consist of coils of wire. These coils of wire at one end are connected to a wire, B' , which leads to an earth-plate, C^2 . At the other end they are severally connected to contact-pieces $J' J^2 J^3 J^4 J^5 J^6$, consisting, as here shown, of metallic springs arranged upon a disk, K , of wood or other suitable insulating material. Through this disk K extends the shaft of one of the wheels c . This shaft is provided with a metal finger, c^2 , which, as the shaft rotates, successively impinges against the contact-pieces $J' J^2 J^3 J^4 J^5 J^6$. This finger is in circuit, owing to the connection of the coils of the electro-magnet G by means of a wire, B^2 , with the frame of the train of wheels, the frame, the wheels, and their shafts being made of metal. Each time the electro-magnets G permit the train of wheels to rotate, the shaft to which the finger c^2 is affixed carries the said finger far enough to break contact with one of the contact-pieces $J' J^2$, &c., and make contact with the next of said contact-pieces, thereby cutting out one resistance-coil and introducing another. The resistance-coil so introduced into the electric circuit is retained in the electric circuit after the lever g resumes its normal position and until the train of wheels are permitted to rotate again. All the resistance-coils may, if desired, be arranged in one spool.

The variation between the resistances $I' I^2$, &c., may be so slight that a change from one to another in the main circuit will not effect the closing of the local circuit and cause the bell F to ring. Generally, however, it will be much greater. Then, the contact-pieces b of the galvanometer in the local circuit will be made adjustable, and can be moved to any position desired—for instance, if the premises were closed up with a resistance in circuit that would cause the galvanometer-needle to stand midway between the contact-pieces, the contact-pieces on each side being adjusted to allow the needle a swing of six points on a scale, and the operator at a later hour desires to place a different resistance in circuit, which I will suppose is less than the coil which was in when the premises were closed, the needle is deflected to the right—say ten points—and the adjustment of the local contacts varied accordingly. Later the operator may desire to throw in another different resistance. This may happen to be a much greater resistance, which would throw the needle to the left of zero, and a change in

the adjustment of the contact-pieces will then be made to correspond with the new position of the needle. It will be better to break the local circuit by a switch or key provided for the purpose before changing the resistance, so that the galvanometer will not sound an alarm, even if its needle should be deflected so as to touch a contact-piece before the adjustment of the latter.

It is obvious that by means of this improvement the watchman at the office may effect a change in the resistance in the guarded structure at will, and by doing so with sufficient frequency can frustrate the efforts of a burglar having knowledge of the resistance in the circuit at the guarded structure at the time of closing the same, to gain access to the guarded structure.

If preferable, an electro-magnetic mechanism may be substituted for the train of wheels, their operating-spring and the electro-magnets for controlling the same. Indeed, I may use in lieu of either, if desirable, a mechanism adapted to run continuously or during any desired periods, and to change the resistance in the electric circuit periodically. This would not be under the control of the operator, and, if not run constantly, would need to be started by the inmates of the guarded structure just preparatory to their leaving the structure.

I have shown in Fig. 2 a piece of mechanism in a guarded structure, resembling a clock in so far as it has a train of wheels impelled by a spring or weight, and a spindle carrying a finger or hand, c^2 , around in a circular path. This hand is of metal, and the wire B^2 is connected to it or its spindle. As it travels around it successively makes contact with contact-pieces $J' J^2$, &c., arranged on a disk and insulated from each other. Wires connect these contact-pieces with different resistances $I' I^2$, &c., and the latter are connected by other wires to a common wire, B' , leading to an earth-plate, C^2 .

Although I have represented my invention in connection with a single-guarded structure, I intend to use it in conjunction with a number of guarded structures connected to a single office, the mechanism described, the main circuits, and the appurtenances of the latter being duplicated for each structure.

To conduce to a clear understanding of my improvement, I have drawn around all devices which are located in the office lines marked "office," and around the guarded structure other lines marked "guarded structure."

What I claim as my invention, and desire to secure by Letters Patent, is—

1. In an electric burglar-alarm, the combination of a galvanometer or other device located at an office or place where watch is kept, and capable of giving an alarm on a certain change of resistance in the circuit, a number of different resistance devices located at a

guarded structure, and a mechanism, also located in the guarded structure, whereby the different resistance devices may be successively introduced into the electric circuit, substantially as and for the purpose specified.

2. In an electric burglar-alarm, the combination of a galvanometer or other device located at an office or place where watch is kept and capable of giving an alarm on a certain change of resistance in the circuit, a number of different resistance devices located at a guarded structure, a mechanism, also located at the guarded structure, whereby the different resistance devices may be successively in-

troduced into the electric circuit, and electro-magnets for controlling said mechanism, substantially as specified.

3. A mechanism consisting of a train of wheels, a weight or spring for actuating the train of wheels, electro-magnets for controlling the operation of the said wheels, a series of resistance devices and means for bringing any of these resistance devices into circuit, substantially as specified.

JAS. TOMNEY.
